CLOTHESPIN

Leslie W. Stinne, Dallas, Tex.

Application August 21, 1945, Serial No. 611,736

5 Claims. (Cl. 24—137)

1

This invention relates to clothespins and more particularly to clothespins of the spring jaw type.

The old and well known type of clothespin, consisting of complementary jaws of wood, held in clamping relation under the tension of a coiled spring, have the objectionable characteristic of springing apart when the jaws are displaced too far in opposite directions laterally. They are difficult to reassemble and more frequently discarded.

It is the chief object of the present invention to provide a clothes clamp or pin whose construction positively prevents accidental dislocation of parts by virtue of a spring member so formed that a portion thereof actually binds the clamp members together at their fulcrum point while the ends thereof are so disposed in relation to the tail portions of the clamp members as to bring the operative ends of the latter together for clamping engagement with the object to be held thereby.

Another object of the invention is to provide a clothespin or clamp in which one of the clamping members is provided with a tongue transverse to the longitudinal axis thereof at its midsection, while the companion member is grooved at a corresponding point thereon to receive the tongue, thereby holding the members for pivotal displacement under the constraining influence of the spring member embracing the same.

With the foregoing objects as paramount, the invention has further reference to certain features of accomplishment which will become apparent as the description proceeds, taken in connection with the accompanying drawings wherein:

Figure 1 is a side elevational view of a clothespin or clamp constructed according to the invention.

Figure 2 is a detail sectional view, somewhat enlarged, taken on line 2—2 on Figure 1.

Figure 3 is a detail perspective view of the spring per se, and

Figure 4 is a rear perspective view of the invention.

Continuing with a more detailed description of the drawing, reference numeral 10 denotes a clamping jaw or member of wood or plastic, not unlike the conventional and well known wooden pin in general appearance but differs therefrom in the provision of a transverse tongue or rib 11 on its inner face at the approximate mid-section thereof. A complementary jaw or clamping member 12 is provided, whose inner surface is transversely grooved at 13 to rockably receive the

2

tongue 11, thus providing a fulcrum for the two members 10 and 12 which will not yield to normal pressures imposed laterally on the members in opposite directions.

Binding the members 10 and 12 for relative movement normally is a spring clip 14, shown in detail in Figure 3. This clip is comprised of a length of spring wire, bent at its mid-section to define a substantially square but incomplete loop 15 which embraces the clamp members 10 and 12 at their fulcrum point. The end portions or arms 16 of the spring wire, before being brought under tension are disposed in the relative positions exemplified in solid lines in Figure 3, and when under tension, they are as shown in broken lines in this figure and lie along and against a side of the tail portions 17 of the members 10 and 12. To preclude any possibility of displacement of the spring clip 14 when the latter is mounted on the clamp members 10 and 12, the faces of these members opposite the fulcrum 11 may be transversely grooved as at a to receive the wire of the loop where it overlies the members 10 and 12. Moreover, transverse grooves b are provided in the confronting faces of the tail portions 17 of the members 10 and 12 to receive the extremities 18 of the wire clip, which are at right angles to the major axes of the clamp members, to exert an outward thrust against the tail portions 17 thereof, thereby holding the forward or operative ends 19 firmly together under tension.

It is obvious from the foregoing that there is little likelihood of the clamp members 10 and 12 becoming displaced laterally by reason of the restraining action of the spring 14 about the waist of the pin, aided by the tongue and groove, which further lends smoothness to the pivotal action of the pin. It is also apparent that the position of the spring on the clamp members precludes engagement thereof with a garment held on a clothesline by the pin. This is considered an important characteristic of the invention because, in many cases, the metal of the spring if not thoroughly cleaned, will stain the fabric or transfer rust thereto unless the spring is made from high grade material immune to rust or corrosion.

Manifestly, the construction as shown and described is capable of some modification and such modification as may be construed to fall within the scope and meaning of the appended claims is also considered to be within the spirit and intent of the invention.

What is claimed is:

1. A clothespin comprising complementary clamping members having a tongued and grooved

fulcrum at their mid-sections, a spring clip formed into a partial loop binding the mid-section of said members about said fulcrum, said loop having arms at right angles to the plane of said loop to lie along one side of the tail of each of said members and whose extremities are at right angles to the major axes of said members to lie in grooves in the confronting faces of the tails of said members to impose counter-pressure thereon to exert a clamping force to the jaws of the latter.

2. As a new article of manufacture, a clothespin comprising clamping members, one of which has a tongue at its mid-section lying in a groove on the confronting face of the companion member, a spring clip formed to define a partial loop embracing the mid-section of said members to bind the same in assembly, said loop having arms lying against the side of said members and extending towards the tail portions thereof whose extremities bear against the confronting faces of the tail portion of said members at right angles thereto to exert counter-pressure thereon.

3. As a new article of manufacture, a clamp including coacting clamp members capable of relative rocking displacement on their confronting faces, a wire loop extending partially around the waist of said members in assembly in close proximity thereto to bind the same together and having arms extending towards the tail portions of said members and whose extremities are disposed to lie at right angles against confronting faces of the tail portions of said members to urge the forward end of said members together under tension.

4. As a new article of manufacture, a clamp

including complementary clamp members held against lateral displacement at their mid-sections, a loop of resilient material partially embracing the mid-section of said clamp members to bind the same in assembly and having arms extending towards the tail portions of said members whose extremities are disposed at right angles to the major axes of said members to bear against and exert outward pressure upon the tail portions of said members.

5. As a new article of manufacture, a clamp including clamp members pivotally displaceable on a transverse fulcrum at their mid-sections and a resilient element partially embracing said elements at their mid-sections to bind the same together, said element having arms, one lying alongside of said members towards the tail portions thereof and whose extremities are adapted to lie transversely across and impose counter-pressure on the tail portions of said clamp members.
